Primary Examiner—Stella Reid*Assistant Examiner*—Eric Watterson*Attorney, Agent, or Firm*—George A. Bode[57] **CLAIM**

The ornamental design for a safety shield for the end cap in a piping system, as shown and described.

DESCRIPTION

FIG. 1 is a top front and left side perspective view of a safety shield for the end cap in a piping system showing my new design, the broken lines showing of a pipe and pipe joint is for illustrative purposes only and forms no part of the claimed design;

FIG. 2 is a front elevational view thereof;

FIG. 3 is a right side elevational view thereof, the side opposite being a mirror image of that shown;

FIG. 4 is a top plan view thereof;

FIG. 5 is a bottom plan view thereof; and,

FIG. 6 is a rear elevational view thereof.
